BUTTON PROTECTOR PAD FOR DRYING MACHINES

Sam M. Hyman, Manitowoc, Wis.

Application December 30, 1947, Serial No. 794,691

10 Claims. (Cl. 259—1)

1

This invention relates to cushion pads for use on baffles of rotary drums in drying machines in the cleaning industry to prevent button breakage on the garment articles tumbled in the drums.

One object of my invention is to provide the pad structure with a plastic outer layer to increase the wear and heat resistance properties of the pad.

A further object of my invention is to provide the pad with a cushion layer protected by canvas and the plastic layers.

A further object of my invention is to provide the plastic layer in folded form to increase the cushioning factor of the plastic layer to prevent button breakage.

The invention consists further in the features of structure and combination of parts herein-after described and claimed.

In the accompanying drawings:

Fig. 1 is a side elevational view of a drying machine partly broken away and in vertical section to show the rotary drum therein with the pad devices of my invention applied to the baffles of the drum;

Fig. 2 is a vertical sectional view on an enlarged scale taken on line 2—2 of Fig. 1, the showing being in perspective to indicate the length of a baffle;

Fig. 3 is a fragmentary top plan view of my improved pad; and

Fig. 4 is a transverse sectional view taken on line 4—4 of Fig. 3, to show details of the pad construction.

In the drawing, 1 indicates the outer casing of a machine of the character employed in cleaning establishments in the process of cleaning fabric and/or garment articles. 2 indicates the rotary drum mounted in said machine to receive and impart a turbulent or tumbling action to articles within the drum. The drum 2 is mounted for rotation about a horizontal axis and is fashioned of the desired relatively light, rigid, metal, such as stainless steel, and has a surrounding cylindrical, wall 3, an end wall 4 at the rear or inner end of the drum and a wall 5 at its front end. Here, the front wall 5 has a relatively large central opening 6 through which the fabric articles are passed in loading and unloading the drum.

The drum 2 is arranged with its front opening 6 adjacent to the main opening in the machine casing 1 to be opened and closed by a hinged door 7 having a handle 8 and a slight opening covered by a transparent panel (both not shown) so that the interior of the drum may be viewed while in operation.

2

The machine is equipped with an electric motor 9 having a belt drive 10 with a pulley 11 on the drum 2 for rotating the same, the showing in this respect being for illustrative and not limiting purposes.

The drum 2 is provided with a series of interior baffles 12 secured to and extending radially inward from the cylindrical wall 3. The structure here may be of the form desired. Specifically, the baffles 12 shown are fashioned of the same metal as the drum walls and are substantially U-shaped in form with substantially parallel, flat, side walls 13, 13 joined by a rounded or curved wall section 14 at the outer edge of the baffle.

15 The side walls 13 of the baffles 12 abut against the inner surface of the drum wall 3 and are secured thereto in any desired manner, a bent over prong construction (not shown) being one form. The prongs are inserted through certain of the 20 perforations 15 provided in the drum wall 3 and clinched thereto. The perforations 15 are shown in Fig. 2 and in the actual machine are distributed over the drum wall 3 to provide openings for the passage of the vapors of the cleaning solvent 25 and the heated air flowed through the machine and the drum in a drying operation.

The cushion pad of my invention is used with each baffle 12 as indicated in Figs. 3 and 4. The pad which is marked 16 is applied over the outer 30 surface of the baffle 12 and provides a cushion to prevent breakage of the buttons or other projections on the garments when tumbled within the drum. It will be noted from Figs. 1 and 2 that the pad 16 fits completely over the baffle 12 about its rounded outer edge 14 and extends relatively close to where the side walls 13 of the baffle abut the drum wall 3. Moreover, the pad 16 is substantially co-extensive in length with the baffle 12.

In accordance with my invention, the pad 16 40 comprises a layer construction, a base layer 17 substantially co-extensive with the length and width of the pad and a pair of outer layers 18, 18a at the opposite sides of the pad and overlapping the base layer 17 along its longitudinal marginal portions. The layers 17 and 18, 18a are 45 preferably of canvas or canvas-like material and are secured together along the outer longitudinal edges of the base layer by over-cast or binding loop stitching 19, 19 as indicated in Figs. 3 and 4. The outer layers 18, 18a are confined to the sides of the pad and terminate short of each other along the central longitudinal portion of the pad.

Arranged in the pad structure is a plastic layer 50 55 extending between the opposed, spaced, edges of the outer layers 18, 18a and secured thereto by

overcast stitching 21, 21 as detailed in Figs. 3 and 4.

The plastic layer 20 is disposed to extend over the rounded edge 14 of a baffle 12 and down the sides thereof to guard against wear on the pad by contact of the garment articles and its buttons therewith. The plastic layer 20 is relatively strong to withstand strain and abrasive wear. Also, the outer surface of the plastic layer 20 being smooth and glazed-like allows the garments and its buttons to readily and easily slide over the pad. Moreover, this plastic layer 20 will withstand and not crack under the heat conditions to which the drum may be subjected as in a drier operation, running up to 350° F.

Included in the pad structure 16 is a cushion layer 22 between the base and the outer layers 17 and 18, 18a and directly beneath the plastic layer 20. The cushion layer 22 may be made of cotton or felted-like material and has its side portions extended under the outer layers 18, 18a and there secured to the base layer 17 by stitching 23, 23 as shown in Fig. 4.

To increase the cushioning factor of the pad 16, the longitudinal edge portions of the plastic layer 20 are folded over on themselves as at 24, 24 at the stitching 23, 23. This construction disposes the plastic layer 20 out of flatwise contact with the cushion layer 22 and presents a spacing for increasing the cushioning property of the pad and to enable the pad to protect the garment buttons.

The pad 16 may be secured to the selected baffle 12 in any preferred manner. In the drawing, I have shown a securing means in the form of a series of eyelets or openings 25, 25 adjacent to the side edges of the pad and bound by metal grommets 26, 26, the latter being preferably of brass. Each baffle 12 is provided in its side walls 13 with apertures 27, 27 to register with the eyelets 25 to receive a lacing or lacings 28 to releasably fasten the pads 16 in place. The lacings 28 may be tied together at their free ends on the exterior of the pad, one of the tyings being indicated at 29.

The pad construction is simple and effective in construction. The canvas base layer 17 protects the softer cushion layer 22 from contact with the baffle 12 and the plastic layer 20 and the outer layers 18, 18a protect the cushion layer 22 from contact with the garment articles. The plastic layer 20 gives the pad strength to readily withstand wear and relatively high temperatures without cracking. Hence, my improved pad is stronger and longer lasting than the pads heretofore employed.

Providing the plastic layer 20 with folded margins 24, 24 increases the cushioning property of the pad to prevent button breakage and also reduces undue strain in bending the pad over the baffle member 12. The overcast stitching is also used to bind the end edges of the canvas layers 17 and 18, 18a as indicated at 30 in Fig. 3. It will be noted that the eyelets 25 are beyond the side edges of the plastic layer, being confined to the canvas layers.

The details of construction and arrangement of parts shown and described may be variously changed and modified without departing from the spirit and scope of my invention, except as pointed out in the annexed claims.

I claim as my invention:

1. In a button protecting pad of the character described, a base layer substantially co-extensive with the length and width of the pad, a pair of

outer layers overlapping and secured to the base layer along the longitudinal marginal portions thereof, said outer layers terminating short of each other along the longitudinal central portion of the pad, said base and outer layers being constituted of fabric material, and a plastic layer extending between the opposed, spaced, edges of the outer layers and secured to the latter, said plastic layer serving to increase the wear and resistant properties of the pad.

5 2. In a button protecting pad of the character described, a base layer substantially co-extensive with the length and width of the pad, a pair of outer layers overlapping and secured to the base layer along the longitudinal marginal portions thereof, said outer layers terminating short of each other along the longitudinal central portion of the pad, said base and outer layers being of fabric material, and a plastic layer extending between the opposed, spaced, edges of the outer layers and secured to the latter, said plastic layer being of a folded character to increase its cushioning properties of the pad.

15 3. In a button protecting pad of the character described, a base layer substantially co-extensive with the length and width of the pad, a pair of outer layers overlapping and secured to the base layer along the longitudinal marginal portions thereof, said layers terminating short of each other along the longitudinal central portion of the pad, said base and outer layers being of fabric material, and a plastic layer extending between and secured to the outer layers adjacent to the spaced edges thereof, said plastic layer having its edges folded upon themselves where secured to the adjacent of the outer layers to increase the cushioning properties of the pad.

20 4. In a button protecting pad of the character described, a base layer substantially co-extensive with the length and width of the pad, a pair of outer layers overlapping and secured to the base layer along the longitudinal marginal portions thereof, said outer layers terminating short of each other along the longitudinal central portion of the pad, said base and outer layers being of fabric material, a plastic layer extending between the opposed, spaced, edges of the outer layers and secured to the latter, and a cushion layer interposed between the base and plastic layers and having its marginal portions inserted between the base and the outer layers where the latter are overlapping relation.

25 5. The pad structure of claim 1 characterized by the fact that there are fastening means at the sides of the pad for releasability securing it in its place of use.

60 6. A button protector pad for the baffles of laundering machines and the like, said pad comprising a base layer for application to a baffle to cover the same, and a top layer of plastic material carried by said base layer, said top layer having a slick wear resistant surface for exposure to the button equipped garments under treatment.

65 7. A button protector pad for the baffles of laundering machines and the like, said pad comprising a base layer for application to a baffle to cover the same, a top layer of plastic material carried by said base layer and having a slick wear resistant surface for exposure to the button equipped garments under treatment, and padding material interposed between said base and top layers for cushioning said exposed surface.

70 8. A button protector pad for the baffles of laundering machines and the like, said pad comprising a centrally disposed longitudinally ex-

tended cushion portion adapted to seat upon the projecting edge of a baffle, said cushion portion including a layer of padding material, and a pair of substantially flat longitudinally extended marginal portions disposed at opposite sides of said cushion portion, said marginal portions being adapted to seat on opposite sides of said baffle and having means for attachment thereto so as to retain said cushion portion in place on the baffle.

9. A button protector pad for the baffles of laundering machines and the like, said pad comprising a centrally disposed longitudinally extended cushion portion adapted to seat upon the projecting edge of a baffle, said cushion portion including a layer of padding material, lines of stitching at opposite sides of said cushion portion for retaining said padding material against lateral displacement, and a pair of substantially flat longitudinally extended marginal portions for attachment to the sides of the baffle to retain the cushion portion in place thereon.

10. A button protector pad for the baffles of laundering machines and the like, said pad comprising an elongated base layer for application to a baffle to substantially cover the projecting edge and sides of the baffle, elongated side layers fixed to and covering marginal portions of said base layer to reinforce the same, an elongated central layer connecting said side layers and spaced from said base layer, and a layer of padding material between said central layer and said base layer.
